US0D1103794S

(12) **United States Design Patent** (10) Patent No.: **US D1,103,794 S**
(45) Date of Patent: ** Dec. 2, 2025

(54) **REAR SENSOR HOUSING**

- (71) Applicant: **Waymo LLC**, Mountain View, CA (US)
- (72) Inventors: **YooJung Ahn**, Mountain View, CA (US); **Jared Gross**, Belmont, CA (US); **Thomas Southworth**, Royal Oak, MI (US); **Chun Chen**, Castro Valley, CA (US)
- (73) Assignee: **Waymo LLC**, Mountain View, CA (US)
- (**) Term: **15 Years**
- (21) Appl. No.: **29/946,990**
- (22) Filed: **Jun. 12, 2024**

Related U.S. Application Data

- (60) Continuation of application No. 29/876,962, filed on May 31, 2023, now Pat. No. Des. 1,036,282, which is a division of application No. 29/799,631, filed on Jul. 15, 2021, now Pat. No. Des. 991,807, which is a continuation of application No. 29/688,905, filed on Apr. 25, 2019, now Pat. No. Des. 928,639.

CLAIM

The ornamental design for a rear sensor housing as shown and described.

DESCRIPTION

FIG. 1 is a front perspective view of the claimed design for a rear sensor housing;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines showing the remainder of the rear sensor housing depict environmental structure and form no part of the claimed design.

1 Claim, 4 Drawing Sheets
